TROPHY BASE

Ray E. Dodge, Miami Beach, Fla., and
Michael J. Albanese, Chicago, Ill.

Application August 16, 1957, Serial No. 47,395

Term of patent 14 years

(Cl. D29—23)

FIG. 1

FIG. 2

FIG. 3

Figure 1 is a front elevational view of a trophy base, showing our new design;

Fig. 2 is a side elevational view; and

Fig. 3 is a top plan view thereof.

The back of the article is substantially plain.

We claim:

The ornamental design for a trophy base, as shown and described.
